UNITED STATES PATENT OFFICE.

FRANK M. DALLEN, OF CHICAGO, ILLINOIS.

BURNER.

Application filed January 9, 1922. Serial No. 527,961.

To all whom it may concern:

Be it known that I, FRANK M. DALLEN, a citizen of the United States, and a resident of Chicago, in the county of Cook and State of Illinois, have invented a new and useful Improvement in Burners, of which the following is a full, clear, and exact description.

My invention relates to improvements in burners, and more particularly to that type of burner which utilizes a fluid as a fuel, and it consists in the combinations, constructions, and arrangements herein described and claimed.

15 An object of my invention is to provide a device of the character described which has means for providing a steady feed of fuel to the combustion chamber.

20 A further object of my invention is to provide a device of the character described which is adapted to change a liquid fuel into a combustible gas before the latter is burned.

25 A further object of my invention is to provide a device of the character described which has a novel vaporizing chamber.

30 A further object of my invention is to provide a device of the character described in which a liquid fuel is first vaporized and is then mixed with the desired quantity of air before it is conveyed to the combustion chamber.

35 A further object of my invention is to provide a device of the character described which is simple in construction, efficient for the purpose intended, and which is not likely to easily get out of order.

40 Other objects and advantages will appear in the following specification, and the novel features of the invention will be particularly pointed out in the appended claims.

45 My invention is illustrated in the accompanying drawings, forming part of this application, in which

Figure 1 is a vertical section through the device, parts thereof being shown in elevation,

Figure 2 is a vertical section through another portion of the device, parts thereof being shown in elevation, and

50 Figure 3 is a section along the line 3—3 of Figure 2.

In carrying out my invention, I provide a body portion 1 which has an annular vaporizing chamber 2 therein. A fuel feed pipe 3 communicates with a groove 4 in the body portion 1, the groove in turn com-

municating with the bottom of the chamber 2. It will be observed from Figure 3 that the chamber 2 is practically circular, except for a small portion 5 of the body 1 which fills a portion of the chamber 2. In other words, the chamber 2 resembles a split ring. As shown in Figure 3, the pipe 3 and the groove 4 are disposed adjacent to one end of the chamber 2. An outlet pipe 6 communicates with a groove 7 which in turn is in communication with the other end of the chamber 2. It will be observed however, that the groove 7 communicates with the chamber 2 adjacent to the top thereof and that the groove 4 communicates with the chamber 2 adjacent to the bottom thereof. The pipe 6 supports a sleeve 8 which has secured thereto, an L-shaped pipe 9. The free end of the pipe 9 is provided with a reservoir 10 and a small orifice 11. The pipe 3 carries an elbow 12 which has a sleeve 13 disposed thereabove. The sleeves 8 and 13 are adapted to secure a pan-shaped member 14 to the body portion 1. The body portion 1 has a downwardly projecting annular flange 15 which is adapted to be received in a recess 16 of the member 14. The flange 15 has a plurality of openings 17 for a purpose hereafter described. As clearly shown in Figures 1 and 2, the central portion of the body 1 has a gas chamber 18 in the top thereof, the upper end of the chamber 18 having radially extending openings 19 for a purpose hereafter described. The inner wall of the chamber 18 tapers outwardly. A pipe 20 is frictionally carried by the member 14 and has one end disposed adjacent to the chamber 18 and the other end disposed above the orifice 11.

From the foregoing description of the various parts of the device, the operation thereof may be readily understood. A valve 21 is connected to the pipe 3 by means of a pipe 22, and, when opened, admits fuel from a source (not shown) into the chamber 2. When lighting the burner, the valve 21 is first opened so as to admit a very small quantity of the liquid fuel to flow into the chamber 2. The valve 21 is then closed, and the flame of a blow torch (not shown) is brought into contact with the walls of the chamber 2. This heats the walls of the chamber and changes the liquid in the chamber into a vapor gas which will be forced downwardly through the pipes 6 and 9, and into the reservoir 10. The vapor gas being

lighter than the air, will flow upwardly from the orifice 11 and into the pipe 20. The blow torch must also be applied to the lower end of the pipe 9 so as to sufficiently warm 5 the vapor gas in order to make the latter combustible. The vapor gas in passing from the orifice 11 into the pipe 20, becomes mixed with the air which passes upwardly in the pipe 20 with the vapor gas. It is to 10 be noted that the vapor gas does not merely mix with the air as it flows upwardly in the pipe 20, but mixes with the latter in the right proportion. This gas passes into the chamber 18 and then downwardly from the 15 chamber 18 into the compartment 23 and out through the openings 17. The gas will also flow outwardly through the openings 19. As heretofore stated, the interior wall of the chamber 18 is tapered so as to deflect the gas 20 downwardly into the chamber 23. This construction prevents any back pressure in the pipe 20 due to the gas striking the top of the chamber 18 and rebounding back into the pipe 20. The gas will flow from the pipe 25 20 into the chamber 18, will strike the top wall of the chamber 18, and will then be forced downwardly along the tapered sides of the chamber and into the compartment 23. As soon as the gas flows out through the 30 openings 17, it is ignited by the blow torch and will continue to burn as long as gas is generated. As soon as the gas flows out through the opening 17, the valve 21 may be opened so as to admit more fluid into the 35 chamber 2 which in turn will be changed into a vapor gas. The flames from the openings 17 and 18 will heat the walls of the chamber 2, whereby the fluid in the chamber will be readily turned into a vapor gas. The 40 blow torch may then be dispensed with, and the burner will continue to function as long as the valve 21 is opened.

As heretofore stated, the device is simple in construction and is efficient for the purpose intended. It affords a positive means 45 for changing all of the liquid fuel, first into a vapor gas, and then into a combustible gas, before it is burned. It will also be observed that by merely moving the pipe 20 with respect to the member 14, it will change the 50 quantity of air admitted into the chamber 18 and will therefore change the length of the burning flame. By positioning the outlet groove 7 above the inlet groove 4, I provide a simple means by which the fluid has 55 to be changed into a vapor gas before it is permitted to enter the outlet pipes 6 and 9. Any excess liquid in the chamber 2 will drain back into the groove 4.

I also provide a means by which the quantity of vapor gas which is emitted from the orifice 11 may be varied at will. This means comprises a screw 24 which is mounted in 60 the free end of the pipe 9. It will be observed that the screw 24 has a conical-shaped

head which is adapted to be received snugly in the conical-shaped dome of the reservoir 10. By merely rotating the screw 24, the orifice 11 may be partially or completely closed.

I claim:

1. In a burner, an arcuate-shaped vaporizing chamber, said chamber having a recess at each end thereof, one of said recesses being disposed above the plane of the other recess, an inlet pipe communicating with the lower recess, and an outlet pipe communicating with the upper recess.

2. A burner comprising an arcuate-shaped vaporizing chamber, said chamber having a recess at each end thereof, one of said recesses being disposed above the plane of the other recess, an inlet pipe communicating with the lower recess, an outlet pipe communicating with the upper recess, a second chamber disposed below said vaporizing chamber, and a vertical pipe communicating with said second named chamber, said outlet pipe terminating adjacent to the lower end of said vertical pipe, said second named chamber having outlet openings in the wall thereof.

3. A burner comprising an arcuate-shaped vaporizing chamber, said chamber having a recess at each end thereof, one of said recesses being disposed above the plane of the other recess, an inlet pipe communicating with the lower recess, an outlet pipe communicating with the upper recess, a second chamber disposed adjacent to said vaporizing chamber, and a vertical pipe communicating with said second named chamber, said outlet pipe having a small orifice in its free end, the axis of the orifice being alined with the axis of said vertical pipe, said orifice being spaced below the lower end of said vertical pipe, said second named chamber having outlet openings in the walls thereof, the openings being disposed above and below said vaporizing chamber.

4. A burner of the character described comprising a body portion having an arcuate vaporizing chamber, a gas chamber, said gas chamber being formed with a substantially conical-shaped recess in the upper wall thereof, a vertical pipe communicating with the gas chamber arranged for longitudinal movement, and an outlet pipe leading from said vaporizing chamber and terminating below the lower end of said vertical pipe, 115 said gas chamber being formed with an arcuate depression on the outer upper wall thereof concentric the conical-shaped recess on the inner side thereof, and being provided with perforations through the wall of said gas chamber so that gases from the chamber may pass through the wall thereof into the arcuate recess.
